OVERHEAD ARBOR EDGER

Terry Lonergan, Burnaby, British Columbia, Canada,
assignor to Mainland Foundry & Engineering Ltd.,
Vancouver, British Columbia, Canada

Filed Aug. 26, 1968, Ser. No. 13,280

Term of patent 3½ years

Int. Cl. D15—05

U.S. Cl. D55—1

FIG. 1.

FIG. 4.FIG. 5.FIGURE 1 is an isometric view of the overhead arbor edger, with portions broken away for ease of illustration,
 FIGURE 2 is a top plan view thereof,

FIGURE 3 is a side elevation opposed to the viewing in FIGURE 1,

FIGURE 4 is a view of one end of the edger and,

FIGURE 5 is a view of the opposite end thereof with portions broken away for ease of illustration.

The dominant features of my design reside in the portions shown in full lines.

I claim:

The ornamental design for an overhead arbor edger, substantially as shown and described.
